3 Sheets-Sheet 3

UNITED STATES PATENT OFFICE.

WALTER H. SMITH, OF PITTSBURGH, PENNSYLVANIA, ASSIGNOR TO MILLER SAW-TRIMMER COMPANY, OF PITTSBURGH, PENNSYLVANIA, A CORPORATION OF PENNSYLVANIA.

SHEET-DELIVERY DEVICE.

Application filed June 15, 1928. Serial No. 116,138.

My invention pertains to sheet delivery devices, and has as its principal object the provision of such a device the parts of which will be capable of being moved out of operative position with respect to the machine in connection with which it is being used, so as to give accessibility to other parts of such machine, which will be safe in use and of a simple and economical construction.

10 By way of example, a sheet delivery device constructed in accordance with my invention is described in the following specification, and shown in accompanying drawings, in which:

15 Fig. 1 is a plan of the device, showing the delivery arm and table in their operative relation with the remainder of the machine, and showing the delivery arm in a position intermediate that in which it receives a sheet and that in which it drops a sheet onto the delivery table;

20 Fig. 2 is a view similar to Fig. 1, but showing the delivery arm disconnected from its driving association and dropped forward to a position where it is out of the operator's way, and showing the delivery table swung away for a like purpose.

25 Fig. 3 is a side elevation of the device, looking from the right hand side of Fig. 1, part of the frame work of the machine being broken away; and

30 Fig. 4 is a section on the line 4-4 of Fig. 3 looking in the direction of the arrows.

As my invention relates solely to a construction of the parts in such a manner as to permit them to be removed from out of the way of the operator when desired, and to provide for safety when advantage is taken of these removal facilities, it will not be necessary to describe at length the various mechanical details by which the sheet delivery device herein referred to is actuated and performs its work. In general plan of operation, the delivery device has much similarity to that described in Patent No. 1,145,405, granted July 6, 1915 on the application of Edward Cheshire.

Referring now to the drawing, 10 indicates the platen of a platen printing press, such platen being shown in its open sheet-receiving position. Secured in the front of

this press,—i. e. to the part remote from the type bed,—there may be a complete mechanism for automatically separating sheets from a pile, feeding such separated sheets 55 to the platen 10, delivering the printed sheets from the platen, etc. A large part of this mechanism is of no importance here, and there is only shown, therefore, a portion of the frame 11 of such mechanism, the table 60 12 upon which the sheets are delivered, the arm 13 by which the sheets are delivered from the platen 10 to the table 12, the mounting construction of such table and arm, and the interlocking devices between the latter. 65

The delivery table 12 is provided, along its front edge, with an upwardly extending plate 14 against which the edges of the delivered sheets stack themselves as they are dropped one by one upon the table. The 70 table is further provided, at its right hand side, with a downwardly extending socket 15 which receives a pin 16 extending upwardly from a standard 17 formed upon the frame 11. The socket 15 rests upon the 75 standard 17; and the table 12 is thus supported in such a manner that it can be swung about the pin 16 as a pivot.

Mounted in suitable bearings in the frame 11 is a shaft 18, upon which is loosely 80 mounted the delivery arm 13, which latter carries delivery grippers 19 which are closed upon the printed sheet on the platen and subsequently opened to drop such sheet on the delivery table. The manner of actuating these grippers is not shown but is along the same general lines as that disclosed in Patent No. 1,145,405 above referred to. Secured to the shaft 18, and adjacent to the arm 13, is a sleeve 20 which is connected, 85 by means of an adjusting screw 21 engaging ears formed on the sleeve and the arm, with the delivery arm 13. Thus any rocking movement that is communicated to the shaft 18 and sleeve 20 will likewise be communicated to the delivery arm 13, the adjusting screw serving only to modify the position of the arm with respect to the sleeve. Mounted loosely on the shaft 18 adjacent the sleeve 20 is a quadrant gear 22 which is actuated by a quadrant 23 which receives a 90 to and fro rocking motion from a suitable 95

cam. It will be seen that if the quadrant gear 22 is connected with the sleeve 20 the to and fro motion of the quadrant 23 will effect a to and fro rocking movement of the 5 delivery arm 13.

The sleeve 20 is provided with an outwardly extending boss 24 formed with a slot in which is pivoted, at 25, a key member 26. The outer end of this key member is adapted 10 to enter the corresponding slot of a boss 27 extending outward from the hub of the quadrant gear 22. The key member is provided with a projection 28 adapted to rest upon the bottom of the hub of the boss 27 15 and thereby limit the downward movement of the key member. It is also provided with an outwardly extending ear 29 adapted to be engaged by a spring-pressed latch 30 carried by the boss 27, which latch serves to 20 prevent the key member from accidentally working outward from the slot of the boss 27. When the key member 26 is engaged in the slot of the boss 27 as shown in Figs. 1, 3 and 4, the sleeve 20 is rigidly secured to 25 the quadrant gear 22; so that the delivery arm 13 will participate in the to and fro rocking movements of the quadrant 23. Upon manual release of the latch 30, however, the key member may be swung outward about its pivot until it is disengaged 30 from the slot in the hub 27. When this has been done, the delivery arm and sleeve 20 are freed from their driving connection, and the delivery arm may be dropped forward 35 until the key member 26 rests upon an abutment 31 provided for the purpose upon the frame 11, as shown in Fig. 2. The other parts of the machine may continue to run, the quadrant gear 22 having, of course, no 40 effect upon the delivery arm. In order to provide against the key member 26 accidentally locking with the quadrant gear 22 otherwise than when engaged in its proper slot, such quadrant is provided with a guard 45 flange 32, which prevents any inward movement of the key member except at the correct position.

Mounted in the boss 24 of the sleeve 20, immediately beneath the slot in which the 50 key member 26 is pivoted, is a pin 33 pressed upward by a spring 33^a, the head of which is adapted to be engaged by a lug 34 on the key member 26 in such a manner that when the key member is swung downward to engage 55 in the slot of the quadrant gear 22 the lug 34 will force the pin 33 downward against the action of its spring. The end of the pin 33 is cone shaped and engages the conical inner end of a second spring-pressed pin 35 disposed axially in the shaft 60 18. The outer end of the pin 35 is also conical and engages the conical end of a third spring-pressed pin 36 mounted in a boss 37 which projects inwardly from the 65 standard 17. The socket 15 of the delivery

table 12 is formed with a hole 38, so placed as to register with the pin 36, when the delivery table 12 is in its operative position; so that when the table is in such operative position the pin 36 can enter the hole 38. 70 In order to facilitate the swinging back of the delivery table to a position in which the hole 38 will be in precise register with the pin 36, the standard 17 is provided with a forwardly extending boss 39 in which is 75 mounted an adjustable screw 40 against which the edge of the table 12 may be made to abut when the table is swung into operative position.

It will be observed that the delivery table 80 may be swung out of the way when desired and also that the delivery arm may be loosened and allowed to drop out of the way when desired. Were the delivery table to be swung to one side while the delivery arm 85 was still operating, damage might result, due to a collision between the two. The same dangerous condition would obtain if the delivery arm, having been disconnected, were reconnected without assurance being 90 had that the delivery table was first in its proper position. An accident of either kind is prevented by my construction, since the pin 36 locks the delivery table against being swung about its pivot, and this pin can 95 only be withdrawn by its spring when the key member 26 has been swung upward about its pivot so as to disconnect the delivery arm from its driving mechanism. Likewise, the delivery arm having been disconnected, it can be reconnected only when the delivery table is in its proper position, since only in that case can the pin 36 enter 100 the hole 38, enabling the pin 33 to be depressed so as to allow the key member 26 105 to enter the slot of the boss 27 of the quadrant gear 22.

Having thus fully described my invention what I claim as new and desire to secure by Letters Patent is:

1. In a sheet delivery device, a delivery table, means for mounting said delivery table to permit it to be swung into and out of operative position, a sheet-delivering member, mechanism for actuating said member, releasable connection means between said member and said mechanism, and an interlocking device for preventing swinging of said table except when said connection means is released.

2. In a sheet delivery device, a delivery table, means for mounting said delivery table to permit it to be swung into and out of operative position, a sheet-delivering member, mechanism for actuating said member, releasable connection means between said member and said mechanism, and an interlocking device for preventing reconnection of said releasable connection means when said table is out of operative position.

3. In a sheet delivery device, a delivery table, means for mounting said delivery table to permit it to be swung into and out of operative position, a sheet-delivering member, mechanism for actuating said member, releasable connection means between said member and said mechanism, and an interlocking device for preventing swinging of said table except when said connection means is released and reconnection of said releasable connection means when said table is out of operative position.

10
WALTER H. SMITH.
